Robert N. Roach, Inventor

C. Snow & Co.

UNITED STATES PATENT OFFICE.

ROBERT N. ROACH, OF ATLANTA, ILLINOIS.

DESIGN FOR A PAN OR PLATE LIFTER.

SPECIFICATION forming part of Design No. 30,316, dated March 7, 1899.

Application filed February 8, 1899. Serial No. 704,983. Term of patent 14 years.

To all whom it may concern:

Be it known that I, ROBERT N. ROACH, a citizen of the United States, residing at Atlanta, in the county of Logan and State of Illinois, have invented and produced a new and original Design for a Pan or Plate Lifter, of which the following is a specification.

This invention relates to a new and original design for a pan or plate lifter; and it has for its object to provide a design of this character that shall be both useful and ornamental.

The leading feature of the design resides in a wire body having a U-shaped yoke and a straight handle-loop extended from the closed side of the yoke, said yoke having opposite duplicate segmentally-curved jaws, each being provided with upper and lower parallel members and a U-shaped loop bent outwardly at an obtuse angle from the outer extremities of both members.

Another feature of the design resides in the lower members of the yoke-jaws, having at their inner ends upturned approximately U-shaped terminal hooks disconnected from the upper members of the jaws.

The minor features of the design reside in the handle-loop having parallel arms provided with a right-angular offset or foot at the point of juncture of the inner ends of the upper members of the yoke-jaws and a circular coil arranged within the closed end of said handle-loop.

In the drawings, Figure 1 is a perspective view of a pan or plate lifter embodying the herein-described design. Fig. 2 is a plan view thereof. Fig. 3 is a longitudinal sectional view on the line 3 3 of Fig. 2.

Referring to the drawings, the numeral 1 designates a wire body having a U-shaped yoke 2 and a straight handle-loop 3, said straight handle-loop 3 being provided with oppositely-located arms 4, and at the outer closed end thereof with a circular coil 5. Contiguous to the inner closed end of the yoke 2 the straight handle-loop is provided with a right-angularly-disposed offset or foot 6, which disposes the handle-loop and the yoke in approximately parallel planes. The U-shaped yoke 2 of the wire body is provided with opposite duplicate segmentally-curved jaws 7, each of which jaws is provided with upper and lower parallel curved members 8 and 9, respectively, having substantially the same curvature. The lower curved members 9 of the yoke-jaws 7 are provided at their inner ends with upturned approximately U-shaped terminal hooks 10, disconnected from the upper members of the jaws and lying in a plane substantially below the juncture of said upper members with the arms of the straight handle-loop. At the lower end or terminal of each of the curved jaws 7 the parallel members thereof have bent outwardly therefrom at an obtuse angle thereto a U-shaped loop 11.

What is claimed is—

The design for a pan or plate lifter, herein shown and described.

In testimony that I claim the foregoing as my own I have hereto affixed my signature in the presence of two witnesses.

ROBERT N. ROACH.
